HOLDER FOR YARN CONES AND THE LIKE

Benjamin F. Kells, Cincinnati, Ohio, assignor to
 Container Corporation of America, Chicago,
 Ill., a corporation of Delaware

Application September 21, 1935, Serial No. 41,509

4 Claims. (Cl. 206—65)

This invention relates to a holder for shipping and storing cones wound with rayon, yarn or other material, and more particularly to a holder adapted to be readily nested in a shipping container.

It should be understood that where reference is made herein to "cones" such term means cones wrapped or wound with rayon, yarn or other materials.

10 One object of this invention is to provide a holder that is simple in construction and economical to manufacture and which is adapted to retain a single cone and protect it from abrasion.

15 Another object of this invention is to provide a unitary or individual holder for cones which is adapted to be packed in an enclosing container in nested relation with similar holders in the minimum amount of space.

20 A further object of this invention is to provide a package of assembled cone holders which can be economically manufactured and which will furnish the maximum amount of protection for the cones.

25 These and other objects, not specifically enumerated, though contemplated by this invention, will readily appear to those skilled in the art as the description proceeds.

For a better understanding of the invention 30 reference may be made to the accompanying drawings in which:

Fig. 1 is a plan view of a portion of the top of a container packed with holders made in accordance with the present invention;

35 Fig. 2 is a vertical sectional view of the packed container taken along line 2—2 of Fig. 1;

Fig. 3 is a perspective view of an individual cone holder in set up form; and

40 Fig. 4 is a view of the blank from which the cone holder of the present invention is formed.

In general, this invention pertains to a holder for a cone of yarn or similar material which is adapted to retain the cone in fixed position therein out of contact with the side walls of the holder 45 and adapted to be packed in a shipping container in such a way that a minimum amount of space is consumed.

Referring to the drawings, 10 indicates an ordinary shipping container of any desirable material and 11 indicates an individual cone holder constructed in accordance with the preferred form of the invention.

There is shown at Fig. 4 a view of the blank 50 from which the holder 11 is formed, such blank 55 being preferably formed of corrugated board

although any other suitable type of material may be used. The blank is scored along the lines 12, 13, 14 and 15 to provide a bottom wall 16, two side walls 17, 17 and in the present instance two top flaps 18, 18, although, if desired, only one flap 18 need be provided. The bottom 16 having an opening or aperture 19 formed therein, such opening or aperture preferably being of such a size as to snugly engage one end of a cone, in this instance, the large end. The top flaps 18, 18 10 having openings or apertures 20, 20 formed therein which are preferably of such a size as to snugly engage the other end of the cone, in this instance, the top or small end. The openings 20, 20 being so positioned that, when the flaps 18, 18 15 are folded into overlapping relation with each other as shown in Fig. 3, they register with each other.

The bottom 16 and the top flaps 18, 18 are 20 preferably of such a size that their edges extend somewhat beyond the edges of the material wrapped on the cone to be packed therein so that the side walls 17, 17 will be held out of contact with the material on the cone. Due to the fact that the wrapped cones are in tapered 25 form the side walls 17, 17 of the holder when thus constructed taper towards the top of the holder and are spaced at substantially an equal distance from the wrapping on the cones along their entire length.

After the cone has been inserted in place within the holder 11 the top flaps 18, 18 are 30 preferably secured together in any desired manner such as by means of a piece of gummed tape 21 to prevent displacement of the cone from the 35 holder.

It is to be understood, of course, that the portion 16 of the holder can readily be used to cooperate with the top of the cone and the flaps 18, 18 to cooperate with the bottom of the cone 40 if such an arrangement is desired, the portion 16 being referred to herein as a bottom merely by way of illustration.

At Fig. 1 there is shown a number of the holders 11 packed for shipment in a shipping container 10, the cones in the holders 11 being indicated at 22, 22.

In packing the cones and holders in the shipping case they are preferably packed, in order 50 to employ the minimum amount of space, in the manner shown in Fig. 1, that is, one row of cones is inserted in the container longitudinally thereof with the axes of the cones in alignment with each other in such a manner that the bottom 16 of one holder will abut the top 18 of the next 55

holder thereby permitting the small end of the cone which extends through the apertures 20, 20 to lie within the large end of the cone in the abutting holder; the cones in the adjoining row 5 are placed with their axes in alignment but in reversed direction to the cones in the first mentioned row whereby the cones in the second row have their large ends lying adjacent the small ends of the cones in the first row. The cones in 10 the other rows are positioned so that alternate rows are the same, as is apparent from Fig. 1.

Due to the fact that the tops 18, 18 of the holder are shorter than the bottoms 16 and flexibility of the holders permits some distortion 15 thereof, it will be seen that when the cones are packed in the manner just described, the holders conform to the shipping container so that the holders adjacent the side walls of the container and holders in the next row which abut them tend 20 to form rectangles and thus by so nesting they require considerably less space than would be required if the tops 18, 18 of the holders were the same size as the bottoms 16.

Any desired number of tiers of cones may be 25 packed within the container 10, each tier being preferably separated from the other tiers by means of a partition 23, as shown in Fig. 2. It is sometimes desirable to insert partitions 24 against the end walls of the box, such partitions 30 having apertures 25 formed therein through which the small ends of the cones, which abut such end walls, may extend to insure better alignment of the cones within the container.

It will thus be manifest that there has been 35 provided a simple and efficient holder for cones which effectively prevents the wrapping on the cones from becoming frayed or otherwise injured by contact with other objects during shipment and one which can be economically and efficiently 40 packed in a shipping container to consume a minimum amount of space.

While the present description sets forth a preferred embodiment of the invention, changes 45 may be made in the construction without departing from the spirit of the invention, and it is therefore desired that the present embodiment be considered in all respects as illustrative and not restrictive, reference being had to the appended claims rather than to the foregoing 50 description to indicate the scope of the invention.

I claim:

1. A unit cone holder package comprising four walls only, namely, a bottom wall, a top wall,

and two side walls, a cone within said holder, said bottom being formed with an opening therein adapted to receive the large end of the cone, said top being formed with an opening therein through which the small end of the cone extends, whereby said holder cooperates with another holder when placed in an outer container in such a manner that the small end of the cone held by one holder lies within the large end of the cone held by the other holder.

2. A multi-unit package comprising an outer container, a plurality of unit cone holder packages disposed therein, each said unit cone holder comprising four walls only, namely, a bottom wall, a top wall, and two side walls, a cone within 15 said holder, said bottom being formed with an opening therein adapted to receive the large end of the cone, said top being formed with an opening therein through which the small end of the cone extends, whereby said holder cooperates with another holder when placed in an outer container in such a manner that the small end of the cone held by one holder lies within the large end of the cone held by the other holder.

3. A multi-unit package comprising an outer 25 container having side walls disposed in right angular relationship to each other, cone holders disposed in said container in a plurality of unit pairs, each unit pair formed of two tapered holders comprising a top and bottom and two side 30 walls joined together, the holders in each unit pair being reversed so that the bottom of one holder is aligned with the top of the other holder, said holders being capable of lateral distortion, whereby the adjacently positioned tops and bottoms of the holders in each unit pair lie in a common plane and the outer side walls of the 35 holders in each unit pair are disposed in right angular relationship to the plane of said respective tops and bottoms.

4. A tapered unit cone holder package comprising four walls only, namely, a bottom wall, a top wall and two side walls, said cone holder being capable of distortion so that one side wall will lie in right angular relationship to the top 45 and bottom walls, said cone holder adapted to cooperate with another similarly distorted cone holder placed in reverse position thereto with the bottom of said last mentioned holder aligned with the top of said first mentioned holder to 50 form a rectangular unit.

BENJAMIN F. KELLS.
